(57) **CLAIM**

The ornamental design for a combination of a door sensor and magnet, as shown and described.

DESCRIPTION

FIG. 1 is a front, right and bottom perspective view of a combination of a door sensor and magnet showing our design.

FIG. 2 is a rear, left and top perspective view thereof.

FIG. 3 is a front, right and bottom perspective view of a door sensor of the combination of a door sensor and magnet of FIG. 1.

FIG. 4 is a rear, left and top perspective view of the door sensor of FIG. 3.

FIG. 5 is a front elevation view of the door sensor of FIG. 3.

FIG. 6 is a rear elevation view of the door sensor of FIG. 3.

FIG. 7 is a left side elevation view of the door sensor of FIG. 3.

FIG. 8 is a right side elevation view of the door sensor of FIG. 3.

FIG. 9 is a top plan view of the door sensor of FIG. 3.

FIG. 10 is a bottom plan view of the door sensor of FIG. 3.

FIG. 11 is a front, right and bottom perspective view of a magnet of the combination of a door sensor and magnet of FIG. 1.

FIG. 12 is a rear, left and top perspective view of the magnet of FIG. 11.

FIG. 13 is a front elevation view of the magnet of FIG. 11.

FIG. 14 is a rear elevation view of the magnet of FIG. 11.

FIG. 15 is a left side elevation view of the magnet of FIG. 11.

FIG. 16 is a right side elevation view of the magnet of FIG. 11.

FIG. 17 is a top plan view of the magnet of FIG. 11; and,

FIG. 18 is a top plan view of the magnet of FIG. 11.

The broken lines shown in the drawings are included for the purpose of illustrating portions of the combination of a door sensor and magnet that form no part of the claimed design.
